REAMER

Luther T. Pedigo, Greensburg, Kans.

Application February 28, 1934, Serial No. 713,363

5 Claims. (Cl. 255—76)

This invention relates to well-drilling machinery.

In many localities, the ground formations are such that it is impossible to drill wells to the required depth without first running in the well casing to shut off caving formations. Very often there are formations encountered which are hard and impervious and prevent the casing from passing on down the hole which has been drilled 10 by a bit that is small enough to pass through the casing. When such formations are encountered, the hole below the casing is enlarged by the use of what is known as an under-reamer, and the present invention relates particularly 15 to the construction of the under-reamer, the object being to provide a reamer of novel construction whereby a simple durable device will be provided comprising few parts and eliminating a large amount of machining which is necessary 20 in manufacturing reamers heretofore known. The invention is illustrated in the accompanying drawings and will be hereinafter fully described, the novel features being particularly defined in the claims following the description.

In the drawings,

Figure 1 is a view, partly in elevation and partly in vertical section, of a reamer embodying the present invention.

Figure 2 is an edge elevation of the same.

Figure 3 is an enlarged detail section showing the cutters swung inwardly into the position assumed when the reamer is being passed down or drawn up through the casing.

Figure 4 is a detail elevation of a portion of the reamer head or body.

Figure 5 is a horizontal section on the line 5—5 of Figure 1.

Figure 6 is a perspective view of one of the cutters removed.

In the drawings, the reference numeral 1 indicates a portion of a casing which has been set into a partly drilled well. The numeral 2 indicates the body or head of my improved reamer which is provided at its upper end with a pin joint 3 for attachment to the regular drilling stem. The body or head 2 is constructed internally with a chamber or recess 4, the side 45 walls of which diverge downwardly, as clearly shown in Figure 1, and from the upper end of which an opening 5 extends through the upper extremity of the head. Spaced below the recess or chamber 4, on each side wall of the 50 body, is a shoulder 6 from which depends a cen-

tral rib or stop lug 7, the sides of the body being open, as shown at 8, whereby circulation of water or other fluid around the working parts is facilitated and, consequently, lubrication of the parts is effected. At its lower end, the body is 60 provided with a tapered or wedge-shaped cross web or rib 9 which is disposed centrally between the sides of the body and serves as a guard to resist and minimize the access of foreign matter to the intermeshing teeth on the cutters, and 65 also as a stop to limit the inward movement of the cutters, all of which will be readily understood upon reference to the drawings.

An adjusting screw eye 10 is mounted in the upper end of the body and has its shank extended through the opening 5, as clearly shown, a lock nut 11 being fitted upon the upper extremity of the shank and seating within a recess 12 provided therefor in the upper end of the pin joint 3, as shown. A coil spring 13 has 70 one end engaged in the eye 14 of this screw eye and its opposite end engaged in the upper end of a V-shaped or bowed leaf spring 15, said leaf spring having its side members diverging downwardly and equipped at their lower ends with 75 eyes or hooks adapted to engage around pins 16 inserted transversely through the upper ends of the cutters. The cutters consist of a substantially cylindrical main portion or body 17 having an opening 18 therethrough to receive 80 a journal pin 19, the ends of which are received in openings 20 in the opposite side walls of the body, said openings being located at the corners of the body at opposite sides of the central vertical plane of the body. On their opposed sides, 85 the cutter bodies 17 are formed with gear teeth 21 which intermesh, as clearly shown in Figures 1 and 3, so that the movement of the cutters will be simultaneous and equal at all times, and it may be noted that there is no strain 90 upon these intermeshing gear teeth, all the strain being carried by the journals 19. On their upper sides, the cutter bodies 17 are formed with spaced lugs 22 which receive the ends of the pins 16 so that the ends of the bowed spring 95 15 will be attached to the cutters and will constantly urge the cutters toward the expanded operating position shown in Figure 1. Connecting the lugs 22 is a web 23 which terminates short of the outer surfaces of the respective 100 lugs to form, when the webs of the two cutters come together, cooperating recesses in the sides of the cutters which will fit around the ribs or stop lugs 7 on the body, as shown in Figure 5, and thereby prevent the cutters swinging out- 105 110

wardly to an excessive degree. The cutting edges or blades 24 project beyond the sides of the respective bodies 17, as will be understood upon reference to Figures 2 and 5, and they are 5 made convex so as to fit readily within the casing or pipe 1, as will be understood. The blades extend from the undersides of the respective bodies 17, as shown clearly in Figures 1 and 6, and at the junction of the blades and 10 the bodies, in the outer sides thereof, are recesses 25 in which are mounted rollers 26 adapted to engage and roll upon the inner surface of the pipe or casing 1, when the reamer is being drawn upwardly or lowered through the 15 pipe, as will be understood. As shown most clearly in Figure 5, the peripheries of the rollers are made convex so that they will conform to the concavity of the pipe and thereby facilitate the passage of the reamer therethrough.

20 The body 2 is provided, on its opposite sides, with vertically extending ribs 27 which will serve to reinforce the body and permit the weight of the same to be minimized, and also will serve as guides to maintain the reamer 25 properly centered within the pipe when being moved therethrough.

It will be understood from the foregoing description, taken in connection with the accompanying drawings, that the spring arms 15 constantly urge the lugs 22 and their connecting webs 23 toward each other so that the cutting edges or blades will swing outwardly beyond the sides of the body 2 to the position shown in Figure 1, to cut through the earth formation 30 which has been encountered and through which the pipe cannot readily pass. The tension of the spring arms 15 will be regulated by adjusting the screw eye 10 so that the cutting edges will rock outwardly whenever they may clear the 40 lower end of the pipe. When the hole has been sufficiently enlarged, the drill stem is drawn upwardly in the usual manner and the cutters will impinge against the lower end of the pipe, the rollers 26 engaging the pipe and yielding to 45 the impact so that the force of the spring arms will be overcome and the cutters will be rocked inwardly to the inoperative position shown in Figure 3. As before stated, the movement of the cutters will be equal and simultaneous, owing 50 to the presence of the intermeshing teeth 21, and access of clay or other foreign matter to the teeth in such quantities as to interfere with their successful operation will be prevented by the guarding extension 9. The device is exceedingly simple and compact and as there are 55 but few parts, it is not apt to get out of order and will prove durable and efficient in use at all times.

Having thus described the invention, I claim:

60 1. An under-reamer comprising a body, cutters journaled in the lower end of the body to rock outwardly to operative position or inwardly to inoperative position and provided with intermeshing gear teeth on their opposed surfaces, interengaging elements on the cutters and the

body to limit the relative outward movement of the cutters, and a spring mounted in the body and connected with the cutters to constantly urge them outwardly toward operative position.

2. An under-reamer comprising a body having 80 a recessed portion in its lower end and provided with transverse shoulders on the inner walls of said recessed portion, stop lugs depending from said shoulders, cutters journaled in the lower end of the body below the shoulders to rock outwardly to operative position or inwardly to inoperative position and provided with intermeshing gear teeth on their opposed surfaces, stop elements on the upper sides of the cutters adapted to impinge against the stop lugs on the body to limit outward movement of the cutters, and springs mounted in the body and connected to the upper sides of the cutters to constantly urge them outwardly toward operative position.

3. An under-reamer comprising a chambered body provided with a transverse extension at its lower end, cutters journaled in the lower end of the body at opposite sides of said extension to rock outwardly to operative position or inwardly to inoperative position and provided with 100 intermeshing teeth on their opposed surfaces in the vertical plane of said extension, springs mounted in the chamber of the body and connected with the upper sides of the cutters to constantly urge them outwardly toward operative position, and interengaging means on the cutters and the body to limit their outward movement.

4. An under-reamer comprising a chambered body provided with transverse shoulders on the 110 side walls of its chamber and depending stop lugs at the centers of said shoulders, cutters journaled in the body below the shoulders at opposite sides of the stop lugs to rock outwardly to operative position or inwardly to inoperative 115 position, lugs on the upper sides of the cutters adapted to impinge against said depending stop lugs to limit the outward movement of the cutters, webs connecting the lugs on the respective cutters and adapted to impinge against each 120 other in movement of the cutters to operative position, and springs connected with the upper ends of the cutters and housed within the body to constantly urge the cutters outwardly toward operative position.

5. An under-reamer comprising a chambered body, cutters journaled in the lower end of the body to rock outwardly to operative position or inwardly to inoperative position and provided with intermeshing gear teeth on their opposed 130 surfaces and having expanded convex cutting edges on their outer lower sides and being provided in their outer surfaces with recesses, rollers mounted in said recesses and adapted to roll upon the inner wall of a well casing, and 135 a bowed spring housed within the chamber of the body and having its ends connected with the cutters to constantly urge the cutting edges outwardly to operative position.
